UNITED STATES PATENT OFFICE.

EDWIN STANTON PORTER, OF NEW YORK, N. Y.

DESIGN FOR A FILM-REEL.

57,860.

Specification for Design.

Patented May 10, 1921.

Application filed September 14, 1920. Serial No. 410,337. Term of patent 7 years.

To all whom it may concern:

Be it known that I, EDWIN S. PORTER, a citizen of the United States, and a resident of the city of New York, borough of Manhattan, in the county and State of New York, have invented a new, original, and ornamental Design for a Film-Reel, of which the following is a specification, reference being had to the accompanying drawing, forming part thereof.

Fig. 2 is a plan view.

I claim:

The ornamental design for a film reel substantially as shown.

EDWIN STANTON PORTER.
